UNITED STATES PATENT OFFICE.

PERRY S. BAUER, OF CHICAGO, ILLINOIS, ASSIGNOR TO BAUER & BLACK, OF CHICAGO, ILLINOIS, A CORPORATION OF ILLINOIS.

NON-RAVELING BANDAGE.

1,206,801.

Specification of Letters Patent.

Patented Dec. 5, 1916.

Application filed May 4, 1916. Serial No. 95,464.

To all whom it may concern:

Be it known that I, PERRY S. BAUER, a citizen of the United States, residing at Chicago, in the county of Cook and State 5 of Illinois, have invented certain new and useful Improvements in Non-Raveling Bandages, of which the following is a specification.

This invention relates to surgical bandages and a method of making same and has for its principal object the provision of 10 relatively inexpensive non-raveling bandages and a method whereby such bandages may be manufactured with the greatest facility in any desired width.

Further objects and advantages of my 15 invention will be apparent as it is better understood by reference to the following specification when read in connection with 20 the accompanying drawing, illustrating the preferred embodiment thereof, in which—

Figure 1 is a diagrammatic view illustrating the method of manufacturing bandages according to my invention; Fig. 2 is a 25 view in perspective of a section of fabric treated according to my method, and Fig. 3 is a view in perspective of a portion of the finished bandage.

I am aware that non-raveling bandages 30 have been manufactured heretofore in which pairs of warp threads coarser than those employed in the body of the fabric are woven into the fabric at intervals. Bandages are not, however, customarily manufactured by weavers of the fabric and inasmuch as the demand for bandages of any 35 particular width varies and cannot be anticipated it has previously been impossible to supply at short notice quantities of non-raveling bandages of this character conforming to definite specifications of width unless a supply of the fabric having the pairs of coarser warp threads properly spaced is at hand. It will be apparent, 45 therefore, that a method which makes it possible for the manufacturer to readily supply non-raveling bandages conforming to definite specifications of width without recourse to the weaver and the product resulting from this method fill a long-felt need in the art.

My method of manufacturing non-raveling bandages comprises stitching the fabric in pairs of contiguous parallel lines, the 55 pairs of contiguous lines of stitching being

spaced apart a distance substantially equal to the width of the bandages, and subsequently cutting the fabric between the contiguous lines of stitching. Bandage fabric is supplied in rolls, as indicated at 60 5 in Fig. 1 of the drawing, and may be separated into bandages of the desired width by suitable machines such as those disclosed in the patents to Otto C. Schulz No. 1,026,283 and No. 1,109,184, granted 65 May 14, 1912 and September 1, 1914, respectively. Preferably as the fabric 6 is withdrawn from the roll 5 it is stitched in a plurality of contiguous parallel lines 7, the stitching means (not shown) being adjustably arranged so that the pairs of contiguous lines of stitching 7 may be spaced at will in accordance with the specified width of the bandages. Bandages of varying widths may obviously be prepared from the 75 same roll of fabric. After the stitching has been accomplished the fabric may pass directly to the cutting disks illustrated in the above-mentioned patents or the material may be re-rolled and subsequently cut manually or on suitable machines.

To better illustrate the method the fabric 6 is illustrated in Fig. 1 as separated at 8 between the lines of stitching 7 forming 80 separate bandage strips. 85

Fig. 2 illustrates on a somewhat larger scale the fabric 6 provided with the contiguous lines 7 of stitching ready for the cutting operation, the separation of the fabric 6 into bandage strips 9 being also indicated.

Fig. 3 illustrates the appearance of a section of a finished bandage 9 provided at either edge with stitching 7 which effectually prevents the warp threads from raveling. Raveling has been a common defect of many forms of fabric bandages despite the attempts of manufacturers to remove the loose warp threads at the edges of the bandages and is a serious disadvantage inasmuch as detached threads are likely to become embedded in a wound which must sometimes be opened after it has partially healed to remove this foreign material.

It will be readily understood from the foregoing that I have perfected a non-raveling bandage which has numerous advantages over bandages as known in the prior art and that my method of making such bandages is superior to methods heretofore employed inasmuch as I am enabled to pre- 105 110

pare bandages of any desired width as rapidly as the fabric can be cut.

It will be apparent that various changes may be made in the form, construction and arrangement of the parts without departing from the spirit and scope of the invention or sacrificing any of its material advantages, the form hereinbefore described being merely a preferred embodiment thereof.

10 I claim:

1. A method of making fabric bandages which comprises stitching the complete fabric in pairs of contiguous parallel lines, the distance between the pairs of contiguous lines of stitching being substantially equal to the desired width of the bandage, and subsequently cutting the fabric between the contiguous lines of stitching.

2. A method of making fabric bandages which comprises stitching the complete fabric in pairs of contiguous parallel lines,

varying the distance between the pairs of contiguous lines of stitching to conform substantially to the desired width of the bandages, and subsequently cutting the fabric between the contiguous lines of stitching. 25

3. As an article of manufacture, a surgical bandage having a thread stitched to the fabric in spaced relation with its lateral edges, whereby raveling is prevented. 30

4. As an article of manufacture, a surgical bandage cloth having a plurality of pairs of contiguously disposed threads stitched to the complete fabric, the distance between the pairs of contiguously disposed threads being 35 substantially equal to the desired width of individual bandages.

PERRY S. BAUER.
